UNITED STATES PATENT OFFICE.

WILLIAM A. ROBBINS, OF GLEN RIDGE, NEW JERSEY.

DESIGN FOR AN AUTOMOBILE-TIRE.

48,991.

Specification for Design.

Patented May 2, 1916.

Application filed January 13, 1916. Serial No. 71,982. Term of patent 7 years.

To all whom it may concern:

Be it known that I, WILLIAM A. ROBBINS, a citizen of the United States of America, residing at Glen Ridge, in the county of Essex and the State of New Jersey, have invented a new, original, and ornamental Design for Automobile-Tires, of which the following is a specification, reference being had to the accompanying drawing, forming a part thereof.

Figure 1 is a perspective view of a tire, showing my new design. Fig. 2 is an en-

larged fragmental perspective view of a portion of the tire shown in Fig. 1, showing one tread design thereon, and Fig. 3 is a plan view of a fragmentary portion of the tire.

I claim:

The ornamental design for an automobile tire, as shown.

WILLIAM A. ROBBINS.
